EARTH AUGER

John C. Jaques, Denison, Tex.

Application March 21, 1946, Serial No. 655,950

7 Claims. (Cl. 255—19)

1

This invention relates to new and useful improvements in earth augers.

One object of the invention is to provide an improved earth auger particularly adapted to be attached to the front end of an ordinary tractor.

Another object of the invention is to provide an improved earth auger including elements which may be readily attached to the front end of an ordinary tractor without altering the structure of the tractor and in a simple manner.

A further object of the invention is to provide an improved auger including a gear housing which carries the auger and its adjusting means and is braced and held against lateral displacement and at the same time is vertically adjustable by the driver of the tractor.

Still another object of the invention is to provide an improved auger feeding mechanism readily adjustable by the workman standing at the hole being bored.

A construction designed to carry out the invention will be hereinafter described together with other features of the invention.

The invention will be more readily understood from a reading of the following specification and by reference to the accompanying drawings, wherein an example of the invention is shown, and wherein:

Fig. 1 is a perspective view of a tractor equipped with an earth auger constructed in accordance with the invention.

Fig. 2 is an enlarged vertical, sectional view of the auger feeding and raising mechanism.

Fig. 3 is a view at right angles to Fig. 2, taken on the line 3—3 of Fig. 2.

Fig. 4 is an enlarged vertical, sectional view of the gear housing and component parts.

Fig. 5 is a transverse, sectional view of the drive pulley and shield.

Fig. 6 is a detail of the telescoping brace, and

Fig. 7 is a transverse, sectional view of the universal joint connections for the shield and torque tube.

This application is filed as a continuation-in-part of my co-pending application filed September 9, 1944, Serial No. 553,311.

In the drawings, the numeral 10 designates an ordinary tractor which has the usual take-off or driving pulley 11, having one end of an endless belt 12 carried thereby. The belt 12 passes over a take-up pulley 13 and has its front end supported on a roller-type pulley 14 mounted on a stub shaft 15 in a cylindrical shield 16 suitably fastened on the front end of the tractor frame 10. Take-off drives of this character are quite

2

common and the details are immaterial to the present invention. As shown in Figs. 1 and 5 the shield 16 extends laterally from the tractor frame and has a window 16' in its rear side through which the belt extends. The stub shaft 15 is connected to a drive shaft 17 by a universal joint 15' and the shaft 17 is enclosed within a torque tube 18 which is connected to the shield by a universal joint 19 (Fig. 7).

10 The torque tube 18, as best shown in Fig. 4, is provided at its outer end with a flange 20 which is secured to the flange 21 of a cylindrical gear housing 22. The flange 21 is formed on the outer end of the collar 23 at one side of the housing and the flange 20 is secured thereto by means of bolts 24. The housing 22 has an enlarged central opening 25 in its top and bottom walls and is provided with an upper cap 26 and a lower cap 27, secured to the housing by bolts 28.

20 An upright cylindrical hood or housing 34 having its upper end closed is welded or otherwise fastened at its lower upper end on the housing cap 26. A boring shaft 35 extends axially through the housing and its caps and also axially upwardly in the hood 34. A stub shaft 37 is journaled in suitable roller bearings 38 mounted in the collar 23. The outer end of this shaft is splined into the reduced outer end of the drive shaft 17. On the inner end of the shaft 37 a bevelled pinion 39 is secured and drives a ring gear 40 rotatably mounted in the housing 22. The pinion and gear are of the spiral tooth type. The ring gear has an elongate depending hub 41 which extends through roller bearings 43 mounted in the lower end of the housing cap 27.

30 The boring shaft 35 has a snug sliding fit in the hub 41 and also in a gear sleeve or block 44 which is integral with the gear 40. The shaft is provided with a vertical key way 45, and a vertical key 46 fastened in the block 44 engages in the key way and thereby transmits rotary motion to the shaft which at the same time is vertically adjustable through the hub and block. The block 44 has an upstanding integral sleeve 47 at its upper end engaging in a roller bearing 48 mounted in the upper end of the upper cap 26. The sleeve extends through a guide collar 49 suitably fastened on the cap 26 in the hood 34; the shaft having a snug sliding fit in said sleeve.

40 A suitable auger bit 50 is mounted on the lower end of the shaft 35. Any bit suitable for the purpose may be employed and a bit of the usual type is shown, which bit includes a tubular shaft 51 having the shaft 35 secured by a coupling 52 in the upper end thereof. By operating the cou-

pling, the bit may be taken off and either sharpened or replaced.

One of the particular features of the invention resides in the manual adjustment and control of the boring shaft. As is best shown in Fig. 2, the upper end of the boring shaft 35 is provided with a reduced upright shank 53 screw-threaded at its upper end. A flanged bushing 54 surrounds the shank and rests upon a collar 53' at the base of the shank. This collar is confined by a nut 55 screwed onto the shank which in turn is held in place by a jam nut 56, screwed onto the upper end of said shank. A hanger ring 57 surrounds the bushing and roller bearings 57' are interposed between the bushing and said ring, being confined by the flange of such bushing and the nut 55. The hood 34 is provided with a vertical slot 58 and upper and lower brackets 59 are mounted on the outside of the hood on each side of the slot at the upper and lower ends thereof, 10 for supporting shafts 60 and 61. Sprocket wheels 62 are mounted on the shafts so as to project through the slot as shown in Fig. 2. An endless sprocket chain 63 is mounted on the sprockets and has one of its links connected with the hanger ring 57 by an adapter link 64 connected in the chain.

The shaft 61 (Fig. 3) extends from one side of the brackets 59 and has fastened thereon a sprocket wheel 66, considerably larger in diameter than the lower sprocket wheel 62. This sprocket wheel 66 is driven by an endless chain 67 passing around a smaller sprocket wheel 68 which is mounted above the wheel 66. The wheel 68 is fastened on a shaft 69 mounted in brackets 70 on the hood 34. The shafts 61 and 69 are long enough to support the wheels 66 and 68 at one side of the hood, so that a relatively long crank handle 65, fastened on the outer end of the shaft 69, may be freely rotated. It is obvious that the smaller wheel 68, in rotating the larger wheel 66, will transmit increased force to the shaft 61 and the chain. This will enable the workman to feed the shaft 35 and bit 50 downwardly with increasing force at reduced labor by placing one hand and his weight on the tube 18 and revolving the crank 65 with the other. It will aid in raising the shaft and bit.

For supporting the gear housing 22 and the tube 18, an upright yoke-shaped frame 29 is suitably mounted in the front end of the tractor frame. An ear 71, within the frame at one side of the top thereof, receives the hook 32 of a pulley block 31, to the bottom of which one end of a cable 38 is attached. This cable extends downwardly and through a pulley block 32', having a hook 33 which is engaged in an eye 33' on the upper cap 26 of the gear housing. The cable, after passing through the lower block 33, extends upwardly and through the upper block 31. From the block 31, the cable extends rearwardly and is attached to a lever 72, suitably mounted on the rear of the tractor frame 10' adjacent the driver's seat. By swinging the lever, the cable is manipulated to raise and lower the auger.

It is obvious that the pulley blocks 31 and 33 and the cable therebetween substantially overhangs the tube 18 and consequently, when the cable is moved, the tube and auger will be swung in a vertical arc transversely of the tractor. In order to hold the auger against forward and rearward displacement, once it is vertically adjusted, as well as to hold the hood 38 and bit 50 in an upright position, a brace is provided.

This brace includes a sleeve 73 into which a

brace bar 74 telescopes. The rear end of the sleeve is attached to a universal joint 75 supported by a bracket 76 secured to the side of the tractor frame 10', at the medial portion thereof (Figs. 1 and 6). The bar and sleeve are provided with spaced holes 77 and 78 adapted to register and receive a headed pin 79, whereby the bar and sleeve are fastened in longitudinally adjusted positions.

The forward end of the bar carries an ear 80 which is pivoted to a clamp 81 secured about the tube 18, intermediate the ends thereof. When the gear housing 22 is adjusted vertically, the pin 79 is removed and the telescoping relation of the brace member and the universal joint 75, permit the brace to swing accordingly. When the adjustment has been made, the pin is inserted in the holes; a slight longitudinal adjustment of the brace members sometimes being necessary to register said holes.

In the usual operation of machines of this character, the tractor is driven by one workman and a second workman manipulates the boring mechanism. By means of the manual chain adjustment, the second workman may stand at the hole and readily adjust the boring shaft 35 up and down as may be necessary. This is a great advantage because it gives the second workman absolute control over the boring and enables him to free the bit 50 in accordance with the boring conditions or to readily raise the same if he so desires. It is obvious that the manual control is more or less sensitive so that the operator can feed the bit to the earth as he desires and if the resistance to the cutting becomes too great he can readily raise the bit to ease off the boring. The driver of the tractor may operate the lever 72 so as to actuate the cable 38 and swing the auger in a vertical arc having its center along the line between the universal joints 19 and 75. The auger may thus be tilted in a vertical plane, and by properly positioning the clamp 81, the auger may be adjusted into any desired vertical position. Plumb holes 40 may thus be drilled.

The foregoing description of the invention is explanatory thereof and various changes in the size, shape and materials, as well as in the details of the illustrated construction may be made, 50 within the scope of the appended claims, without departing from the spirit of the invention.

What I claim and desire to secure by Letters Patent is:

1. An earth auger for a tractor having a frame 55 including, a torque tube member having one end pivotally connected to the tractor frame and its opposite end extending horizontally thereof, a brace member having its inner end pivotally connected to the tractor frame and its outer end pivotally connected to the torque tube member, one of said members extending transversely of the tractor frame and the other member extending longitudinally of the tractor frame, a gear housing 60 having gearing therein mounted on the outer end of the torque tube member, a gearing shaft 65 connected with the gearing of the housing and extending through the torque tube member, means for driving the gearing shaft adapted to be connected with the driving mechanism of a 70 tractor, an upright boring shaft slideable through the gearing of the housing and rotated thereby, means carried by the housing for vertically adjusting the boring shaft, a bit mounted on the lower end of the boring shaft, and means connected to the tractor for vertically adjusting the 75

5

gear housing, the pivotal connection of the torque tube member and brace member to the tractor frame allowing vertical movement of the housing and bit and rigidly holding the housing and bit against lateral movement.

2. An earth auger for a tractor having a frame including, a torque tube member having one end pivotally connected to the tractor frame and its opposite end extending horizontally thereof, a brace member having its inner end pivotally connected to the tractor frame and its outer end pivotally connected to the torque tube member, one of said members extending transversely of the tractor frame and the other member extending longitudinally of the tractor frame, a gear housing having gearing therein mounted on the outer end of the torque tube member, a gearing shaft connected with the gearing of the housing and extending through the torque tube member, means for driving the gearing shaft adapted to be connected with the driving mechanism of a tractor, an upright boring shaft slideable through the gearing of the housing and rotated thereby, an upright housing mounted on the gear housing and enclosing the boring shaft, an endless chain mounted on the upright housing, a connection carried by the chain and rotatably connected with the boring shaft for vertically adjusting the latter, hand means carried by the upright housing for operating the chain, a bit mounted on the lower end of the boring shaft and means connected to the tractor for vertically adjusting the gear housing, the pivotal connection of the torque tube member and brace member to the tractor frame allowing vertical movement of the housing and bit and rigidly holding the housing and bit against lateral movement.

3. An earth auger as set forth in claim 1, and an upright frame mounted on the tractor and having the gear housing adjusting means connected thereto.

4. An earth auger as set forth in claim 1 with a split clamp secured around the torque tube member and the outer end of the brace member pivotally connected to the clamp.

6

5. An earth auger as set forth in claim 1 with a split clamp secured around the torque tube member and adjustable thereon and the outer end of the brace member pivotally connected to the clamp, said brace member being adjustable lengthwise.

6. An earth auger for a tractor having a frame including, a torque tube member having one end connected to the tractor frame and its opposite end projecting horizontally thereof, a universal joint in said tube member near its connected end, a brace member having its inner end connected to the tractor frame and its outer end pivotally connected to the torque tube member, a universal joint in the brace member near its inner end, one of said members extending transversely of the tractor frame and the other member extending longitudinally of the tractor frame, a gear housing having gearing therein mounted on the outer end of the torque tube member, a gearing shaft connected with the gearing of the housing and extending through the torque tube member, means for driving the gearing shaft adapted to be connected with the driving mechanism of a tractor, an upright boring shaft slideable through the gearing of the housing and rotated thereby, means carried by the housing for vertically adjusting the boring shaft, a bit mounted on the lower end of the boring shaft, and means connected to the tractor for vertically adjusting the gear housing, the universal mounting of the torque tube member and brace member allowing vertical movement of the housing and the bit and rigidly holding the housing and bit against lateral movement.

7. An earth auger as set forth in claim 6, wherein a split clamp is secured around the torque tube member and adjustable thereon and the outer end of the brace member pivoted to the clamp, said brace member being adjustable lengthwise.

JOHN C. JAQUES.
